PANEL MANUFACTURE

Clarence J. Davies, Detroit, Mich., assignor to National Automotive Fibres, Inc., Detroit, Mich., a corporation of Delaware

Application June 13, 1938, Serial No. 213,515

31 Claims. (Cl. 154—1)

This invention relates to panel manufacture and more particularly to a method and machine for cutting and applying sheet material to a surface.

In the manufacture of automobile trim panels it has been found that the use of a padding material intermediate the panel board and the upholstery material adds to the appearance and utility of the panel board. It has accordingly been the practice to cut padding material to pre-formed shape and to apply the same to the panel board before covering the board with upholstery material. In certain cases it has also been the practice to apply padding material to panel boards by fabricating a continuous web of padding material, for example, cotton fibers, applying an adhesive coated panel board to the web of padding material and brushing away padding material from around the edges of the panel board.

In some cases it has been found desirable to apply padding material to predetermined portions only of the panel board in order to provide portions of the panel board uncovered with padding material, for the purpose of applying the decoration to the upholstery material. More specifically, it has been the practice to remove padding material from certain designated and predetermined portions of the padded board for the purpose of applying preformed risers or strips of deformable material which are adapted to cooperate with the upholstery material in forming relief designs therein.

In the manufacture of panel boards of this type in production, it is obvious that to cut padding material to predetermined shape, if the padding material is selfsustaining in form such as for example, blue wadding, is an expensive process and requires great care in causing the padding material to register exactly with the designated portions of the board which are to be covered. A relatively large number of panels are spoiled due to the fact that the padding material as applied in production does not register exactly.

The present invention provides means for applying padding material automatically to padding boards and is so constructed and arranged that padding material after applying must register with great exactness with the designated areas of the panel board. Briefly described, the present machine involves a knife-edged die, the outline of which corresponds to the outline of the panel board or to so much thereof as will be covered with padding material. Inside the out-

line knife edge are provided a plurality of additional knife edges which are adapted to cut predetermined designs in the padding material. The padding material is automatically fed over the die and is pressed thereagainst by a roller or other means. As the roller passes over the padding material, it causes the knife edges previously referred to to cut the material to predetermined outline, and to cut predetermined patterns within the area of the padding material. This has the effect of cutting padding material to predetermined outline and also cutting separate portions of the padding material free from the main portion thereof. Means are provided on the die for elevating the portions of the padding material which are to be applied to the panel board above the plane of the knife edges and at the same time the portions within the outline of the padding material which are not to be applied to the panel board remain depressed below the level of the knife edges, or at least substantially at the level of the knife edges.

The panel board is then automatically fed in timed relation into contact with the elevated portions of the padding material. A panel board is previously coated with a suitable adhesive and when the panel board engages the padding material, the padding material which is to be applied to the board is released in timed relation from the die member and is thus applied in exactly predetermined position on the panel board.

The machine is entirely automatic in operation and requires only the replacement of completed padded panel boards with adhesive coated panel boards at intervals. The padding material is supplied in continuous or roll form and is intermittently fed over the stationary die member.

With the foregoing brief description of the operation of my machine in mind, the objects of the invention will be apparent.

It is a broad object of my invention to provide a machine for separating sheet material into separate classified areas.

It is a further object of my invention to remove predetermined areas from sheet material and position them separately for further processing. Specifically, it is an object of my invention to provide a machine for cutting and applying sheet material to designated areas of an area.

It is a further object of my invention to cut padding material into a predetermined pattern by means of a die member and to apply the same to a panel board without the intermediate step

of removing the padding material from the die member.

It is a further object of my invention to provide a machine for cutting and applying padding material which is entirely automatic in its operation.

It is a further object of my invention to provide a machine of the class described in which separate organizations are driven intermittently in predetermined relation from a single constantly rotating driving member.

Other objects of the invention will be apparent from the following detailed description and when taken in conjunction with the accompanying drawings, wherein

Fig. 1 is a right hand side elevation of my improved machine;

Fig. 2 is a top plan view of the machine;

Fig. 3 is a left hand elevation of my machine;

Fig. 4 is a front view of my machine;

Fig. 5 is a rear view of my machine;

Fig. 26 is a fragmentary view of the other timing mechanism assembly;

Fig. 27 is an enlarged detail of the panel adjusting means; and

Fig. 28 is an enlarged detail view of the air valve and control means.

The machine shown as a whole in Figs. 1 to 5 inclusive comprises a base 100 to which is rigidly secured a stationary upright frame portion 102 and side members 103, the parts 103 being secured by an intermediate cross frame member indicated in Fig. 1, generally by the numeral 104, the parts 102 and 103 being bolted together. This construction provides a rigid frame assembly for supporting the moving parts subsequently to be described. The moving parts comprise essentially a panel support or carrier 200 which is adapted to reciprocate horizontally toward and away from the upright 102, and roll assembly 300

adapted to be reciprocated vertically in timed relation to the horizontal reciprocation of the panel support 200. The driving means for all the movable parts of the machine comprise a motor 105 carried on the base 100, which constantly rotates a sheave 106. A second sheave 107 is carried between the two upright frame portions 103 by a shaft 108. The sheave 107 rotates freely around the shaft 108 and is adapted to be positively connected thereto by the clutch generally indicated at 500. It is desired during the operation of the machine for the shaft 108 to rotate constantly at a uniform speed and for this shaft to transmit intermittent rotation to the shaft 110 and the panel drive member 111. The rotation of these parts is accurately predetermined by a mechanism subsequently to be described, but it may be stated here that during constant rotation of the shaft 108, the shaft 110 will make one complete revolution and stop, the panel drive member 111 will make one complete revolution and stop, and during the next equal interval, the shaft 110 and the panel drive member 111 are both stationary.

The mechanism for causing vertical reciprocation of the roll assembly 300 is best seen in Figs. 1, 3, 12 and 13. The brackets 301 are secured to the uprights 103 and have formed thereon upstanding apertured lugs 302 to which are trunnioned links 303. Intermediate links 304 are adapted to interconnect links 303 and the carriage 305 which supports the cutting roll member 306, and for this purpose the links 304 are connected as by pins 307 to the links 303, and are correspondingly pivotally connected at 308 to the carriages 305.

The link 304 is provided with an elongated slot 309 in which is mounted for relative sliding motion a block 310 shown in detail in Figs. 12 and 13. Block 310 is provided with interconnected oil passages 311 and a conventional oiler 312 for constantly lubricating the bearing surfaces between the block 310 and the slot 309. The block 310 is centrally apertured as at 313 in Fig. 13 for connection to a crank 312.

The carriages 305 are mounted on ways 314 for vertical reciprocation on the frame or bolster 102. Supported between the carriages and rotatably journaled therein is the cutting roll 306 which, as best seen in Fig. 4, is made up of a plurality of coaxial sections which may be of any suitable material, but which preferably are formed of metal. The carriages 305 and the cutting roll 306 are positioned so as to roll substantially tangent to the knife edges of the die later to be described.

As the cutter roll carriage 305 reciprocates vertically, the roll 306 is positively rotated so that its surface has a true rolling relationship with the die. For this purpose a vertical rack 361 is carried by the frame, and a gear 360 is keyed to the roll supporting spindle. The gear 360 has a pitch diameter equal to the diameter of the roll. The roll is driven in relation to the die so that it presses the padding material into the die without slippage.

Chains 370 and 371 (Fig. 5) are connected to suitable counterweights to balance the weight of the roll 306 and its carriage, being led for this purpose over suitable idler sprockets.

The panel support generally indicated at 200 comprises a panel slide 201 which is mounted for horizontal reciprocation toward and away from the die member on ways 203. Secured to the under side of the panel slide 201 is a depending lug 202 to which is secured one end of the link 204, the other end of which is secured to a crank

205 carried by shaft 206. The driving member 111, best seen in Fig. 2, carries a sprocket 207 and a second sprocket 208 is keyed to shaft 206. The sprockets 207 and 208 are interconnected by a chain 209 and rotation of the sprocket 207 will cause a corresponding rotation of the crank 205 which will result in controlled reciprocation of the panel slide 201 toward and away from the die members.

Means are also provided for automatically feeding a web of padding material downwardly over the exposed face of the die during the downward reciprocation of the cutting roll, generally indicated at 300. Mechanism for accomplishing this result is shown in Figs. 3, 4 and 5. A conveyor belt 320 is supported adjacent the top of the upright 102 and a continuous web of padding material is adapted to be fed by this conveyor to the present described machine. As best seen in Fig. 3, the conveyor belt 320 is actuated by a sprocket 321 driven by a chain 322 which in turn is adapted to be actuated by means subsequently to be described. Rigidly supported by brackets 323 on the uprights 102 is a roll 324 which is adapted to be spring pressed toward the conveyor belt to compress the web of cotton or other padding material against the belt as by a spring 325. The chain 322 is led around the second sprocket 327 supported on the base 100 of the machine. This chain is discontinuous and inserted in the chain is a square rod 328. Supports 329 are carried by the cutting roll carriage and a notched bar 330 is supported in a vertical position intermediate the supports 329. Adjustable blocks 331 are carried by the notched bar 330 and are vertically adjustable thereon. Each adjustable block 331 is provided with a square clearance hole through which is adapted to reciprocate the square rod 328 previously referred to.

From the foregoing description it will be apparent that upon downward motion of the carriage 305 the blocks 331 pass freely over the square rod 328 until such time as the lower block strikes abutment 333 on rod 328, at which time the chain 322 is moved downwardly, rotating sprockets 321 and 327. Rotation of the sprocket 321 is adapted to rotate shaft 335 in a direction to cause forward feeding of the conveyor 320, and corresponding downward feed of the padding material across the face of the die member, the relationship between the feed of the padding material and the cutting roll being such that the free edge of the padding material follows a short distance behind the cutting roll.

When the cutting roll reaches the bottom of its travel and reverses, the blocks 331 will slide over the square rod 328 until such time as the upper block 331 engages the upper projection 333 on the rod. At this time the direction of travel of the chain 322 will be reversed with a corresponding reversal in the direction of rotation of the sprocket 321. However, means are provided to prevent this reverse rotation of the sprocket 321 from causing backward feed of the padding material.

As best seen in Figs. 6 and 7, the sprocket 321 is freely journaled on shaft 335. A one-way clutch member is provided comprising a housing 336 which is secured to and adapted to rotate with the shaft 335, a key 336' being provided for this purpose. The sprocket 321 is mounted for free rotation on the shaft 335. Keyed to the sprocket 321 is a driving member 337 having portions 338 extending into an annular chamber within the housing 336. Portions

338 are substantially radial projections formed by recesses 339 in the periphery of the member 337. These recesses have a flat bottom 340 forming a driving surface and a substantially radial surface 341. Received within each recess 339 are rollers 342, each urged away from the abutment 341 as by a compression spring 343 received within the recess formed within the member 337.

Referring now particularly to Fig. 7, if the driving member 337 which is keyed to the sprocket 321 is rotated in a clock-wise direction, the rollers 342 will be urged away from abutments 341 by the combined action of compression springs 343 and friction with the housing 336. The chambers 339 taper to a smaller cross section and motion of the rollers 342 away from the abutments 341 eventually causes a wedging or driving engagement between the rollers 342, the driving surfaces 340 and the inside surface 20 of the housing 336. At this time rotation of the driving member 337 will be transferred to the shaft 335 through the medium of the clutch housing 336 and the key 336'.

From the foregoing description it will be apparent that upon downward motion of the cutting roll a predetermined and adjustable length of padding material is fed downwardly over the face of the die, and that upon reversal of the cutting roll during which time the cutting roll traverses the face of the die in cutting relation, the feed of padding material is interrupted.

The mechanism which drives the cutting roll and the panel slide in timed relation will now be described. This mechanism is best seen in Figs. 2, 9, 10, 11, 17 and 20 to 26. The gear 116 is adapted to continuously rotate, being driven by suitable speed reduction means 114. This results in a corresponding rotation of gear 117. Referring now to Fig. 17, it will be noted that the gear 117 is keyed or otherwise secured, as indicated at 118 to a coaxial member 119 which is adapted to turn freely on the shaft 110. Member 119 has an annular series of gear teeth 120 formed thereon. Member 119 beyond the teeth 120 has a reduced hub portion 121 upon which is mounted an annular toothed member 122, the outside diameter of the member 122 being somewhat smaller, as shown in Fig. 17, than the toothed portion of member 119. A bracket 123 is carried by a frame portion 104 and supports a pair of small pinions 124 and 125. Pinions 124 and 125 are secured together as by a locking pin and are adapted to rotate as a unit, being mounted for this purpose on a spindle 126. As indicated in Fig. 17, pinion 125 is substantially smaller than pinion 124. These pinions are adapted to mesh constantly with tooth portion 120 and the toothed member 122. It will be evident that annular toothed member 122 will be driven at a substantially different speed from member 119.

The shaft 110 carries a rotatable driving member 127 provided with a recess 128 therein, a spring pressed driving key 129 being received within the recess and urged by the spring in an outward direction, that is, a direction causing it to bear against the hub 121 and the annular toothed member 122. Driving member 127 is connected by driving sleeve 111, to drive sprocket 207, and is mounted for free rotation on the shaft 110.

A substantially identical assembly shown in Fig. 26 is carried on the shaft 110 on the opposite side of the gear 117. This assembly includes a driving member 127' which is keyed to the shaft 110 and rotation of this driving member is there-

fore adapted to rotate the shaft 110 and by mechanism previously described, to cause vertical reciprocation of the cutting roll.

Since these assemblies are substantially identical, with the exception that the driving member 127' is keyed to the shaft 110 and driving member 127 is loosely mounted on the shaft and is adapted to drive sprocket 207, only one of these assemblies will be described in detail. Member 119, as shown in Fig. 20, has a second hub 121' beyond a second annular series of teeth 120'. Formed in the periphery of the hub is a driving slot 130' having one wall thereof interrupted and provided with an inclined surface 131'. The annular member 122' which is adapted to fit over and rotate freely upon the hub 121' has inclined cam surfaces 132' and 133' and an intermediate low portion 134' formed in the edge thereof against which the driving member 127' is adapted to bear.

The driving member 127' shown in Figs. 24 and 25 is provided with an internal groove 135' for receiving a key to connect the driving member to the shaft 110'. A recess 136' is formed in the periphery of the driving member and is adapted to be closed by a plate 137', the plate forming a chamber therein which is closed except for a top opening as best seen in Fig. 26. Received within the recess 136' is a spring pressed driving key 129', the spring best shown in Fig. 26 urging the key outwardly from the recess and into driving engagement with the driving slot 130' on the hub of member 119.

Due to the driving and driven relationship between gears 120' and 122', it will be apparent that gear 122' is driven at a different speed from gear 120'. Due to this difference in relative motion, the low portion 134' on member 122' will register with the driving slot 130' in the hub 121' only at predetermined points in the rotation of the two members. By selecting the number of teeth in gears 120', 122', 124' and 125', the elongated low portion 134' of the annular member 122' may be brought into registry with the driving recess 130' of the hub 119 at some predetermined point in the rotation of the member 121'. Upon every predetermined revolution of member 119, the low portion 134' of annular member 122' will coincide with the driving slot 130' of the hub 121' as the driving slot reaches the spring pressed driving key 129'. At this time, therefore, under the impulsion of the spring previously referred to, the driving key will drop into the driving recess 130', thereby locking driving member 127' and the hub 121' together. The length of the low portion 134' of the annular member 122' is so selected that the low portion 134' will continue to coincide with the driving slot 130' for some predetermined portion of a revolution of hub 121', in the present instance the relationship being such that inclined cam surface 133' will force driving key 129' out of driving connection with the driving slot 130' at the completion of a single revolution of the member 119.

At this time attention is directed to the fact that driving members 127 and 127' are each adapted to drive an ultimate driven member through the medium of cranks and that at the moment of engagement and disengagement between the driving key 129 or 129' and the driving slot 130 or 130' respectively, the cranks are substantially perpendicular to the members which they drive. This results in the fact that at the moment of engagement and disengagement be-

tween the key and its slot, the apparatus is substantially in condition of no load.

It is necessary that the panel be brought into registry with the die member with great nicety, and for this purpose a secondary adjustment is provided on the panel slide, as best seen in Figs. 1 to 4 and 27. As best seen in Fig. 4, panel support 201 is mounted in ways 203 in the legs 250 of the frame. These legs are bolted to the base 100, and are interconnected by tie rods 252, over which are tubular spacers 251. Rods 252 carry nuts 253 for rigidly securing the parts in position. The panel support is adjustable along the ways so that upon actuation of the support toward the die, the panel may be brought into registry with the die with great accuracy. As best seen in Fig. 27, a bracket 231 is secured to the base of the panel slide and an adjustment bar 232 is pivoted as at 233, adjacent the upper portion of the bracket 231. A slot 234 is provided in the base of the panel slide and the adjustment bar 232 depends therethrough and is connected at its lower end to link 204. An eccentric shaft 235 having an eccentric portion 236 is journaled in the bracket 231 and extends through an elongated slot 237 in the adjustment bar 232. A clamping bearing 240 is secured to the base of the panel slide and has a clamping bolt 241 carried thereby. The eccentric shaft 235 has an actuating arm 242 extending laterally therefrom. It will be apparent that upon rotation of the arm 242 the adjustment bar 232 will be moved slightly about its pivot point 233, with the result that there will be a slight adjustment between the link 204 and the panel support. In order to make this adjustment, the clamping bolt 241 is first loosened, the adjustment made and the bolt then tightened to lock the parts in adjusted position. By this arrangement it is possible to provide for the panel being brought to within a very accurately determined distance of the knife edges of the die member.

The die member, best seen in Figs. 14 and 18, is rigidly supported upon the frame of the machine. The die member proper comprises a platen 610 carried by frame part 102, and chase 601 which are clamped together by suitable clamping means indicated at 602, Fig. 14. The forward face of the die may conveniently be formed of blocks 603 of wood or other suitable material separated by knife edges 604 which extend a substantial distance above the forward face of the blocks 603. It will be understood that the knife edges 604 are arranged in any predetermined or fanciful design, one of which is indicated in Fig. 18, and include top cut off rules 620 shown dotted in Fig. 15.

As seen in Fig. 19, which illustrates a panel with the cut padding material assembled thereon, it is desired to cut the padding material in the die into the predetermined design and to separate the same into portions, some of which are to be applied to the panel board and some of which are not to be applied to the panel board. For this purpose, a plurality of resilient blocks 605 which conveniently may be formed of rubber, are placed between certain of the die members, the arrangement being such that all areas of padding material which are to be applied to the panel board are backed with the resilient blocks referred to.

The blocks as shown in Figure 14 are preferably thick enough to elevate sections of padding material completely out of the die recesses, but for certain types and thicknesses of material it may be sufficient to move sections only partly out

of the support, as will be obvious. In such case, of course, the blocks will be of less thickness than the depth of recess. In all cases, however, it is preferred to elevate the outer surface of the sections of padding material a substantial distance above the plane of the knife edges.

At 606 in Fig. 14, is indicated a section of padding material which is not to be applied to the panel board and as indicated in this figure, the resilient block 605 is omitted. The die member is provided with an interior chamber 607 which has a plurality of interconnecting conduits or passages 608, the arrangement being such that passages are provided between the chamber 607 and each area of the panel board adapted to cut a separate section of the padding material. It will be understood that a plurality of such conduits 608 are provided for elongated areas such as extend horizontally across the panel, as illustrated in Fig. 18. The chamber 607 is connected by a pipe 609 to a source of fluid pressure and to a source of fluid suction. Automatic means later to be described are adapted to connect the chamber 607 to the source of fluid pressure or the source of suction in timed relation to the operation of the machine.

The means for controlling the air supply to the chamber 607 is best indicated in Figs. 3, 14 and 28. As best seen in Fig. 3, an air valve generally indicated at 150 is carried by the frame of the machine. Conduit 151 connects to a vacuum tank, conduit 152 connects to a pressure tank, and conduit 153 connects to the T fitting 154 indicated in Fig. 5, for supplying air pressure or suction to the die member. An actuating arm 155 is carried by the valve and is adapted to be actuated by a finger 156 on the cutting roll.

Arm 155 has three positions, the horizontal or full line position being the neutral position in which the valve interrupts connection to both the source of fluid pressure and suction. When arm 155 is depressed, connection is made to suction. When arm 155 is raised, connection is made to pressure.

Finger 156 is adapted to actuate the arm 155 at the completion of the down or non-cutting stroke, and movement of the arm 155 to the down or dotted line position as shown in Fig. 3 interconnects conduits 151 and 153, with the result that suction will be applied to the die member. Arm 155 remains latched in this position during upward movement of the cutting roll. An operating arm 157 is secured to bracket 158, the opposite end of the operating arm being connected to the arm 155, by pins shown in Fig. 28 received in slots 155'. Operating arm 157 has cam surfaces 158 and 159 formed thereon and the panel slide 201 carries a roller 160 adapted to engage these cam surfaces. Roller 160 is carried by an arm 161 which is spring pressed in clockwise direction as seen in Fig. 3, against an abutment 162. Upon motion of the panel slide 201 to the left, the roller 160 engages the cam surface 158 and the cam roller arm 161 is rotated against spring pressure in a counterclockwise direction, thus riding up over the portion of the operating arm 157 intermediate the cam surface 158 and 159.

A trip 163 is carried by the panel slide 201 and is adapted, at substantially the instant the panel slide reaches forward position, to engage the release arm 164 carried by the air valve. Arm 164 acts to release lever 155 to its neutral position. This has the effect of disconnecting conduits 151 and 153 and cutting off suction from the interior

of the die member. The panel slide instantly reverses and during return motion roller 160 engages cam surface 159, thereby depressing operating arm 157, since the roller arm 161 is at this time forced against the supporting block 162. Lowering of the operating arm 157 causes the valve arm 155 to move to upper position, thereby interconnecting conduits 152 and 153 and supplying fluid pressure to the interior of the die member. The valve 150 is so arranged that in this position the arm 155 is not latched and arm 155 will remain in pressure supply position only so long as the roller 160 rides over the high portion of the cam surface on operating arm 157. As soon as the roller 160 drops off the cam surface 158, the valve arm 155 returns to neutral position, thereupon disconnecting conduits 152 and 153 and shutting off the supply of fluid pressure to the die member.

In order to start and stop operation of the automatic mechanism, a clutch 500 is provided and the operating mechanism associated therewith is best seen in Figs. 1, 2 and 8. As best seen in Fig. 8, a sheave 107 is supported for free rotation on the shaft 108, for this purpose being keyed to a bearing member 501 which is mounted for rotation by means including suitable roller bearings 502. This structure also carries an annular member 503 formed with an annular projection 504. Extending inwardly from the lateral projection 504 and supported therefrom by suitable securing means indicated at 505 is a clutch bearing ring 506. Keyed to the shaft 108 as indicated at 507 is a member 508 which has a radially extending bearing portion 509 carried thereby. The member 508 also carries a second radially extending bearing member 510, this member being mounted for axial movement relative to member 509. A spring 511 is received between members 509 and 510 and tends to cause relative movement between these members to separated position.

Also carried by member 508 are a number of levers 512 having projections 513 thereon. Levers 512 are adapted to be moved about pivots 514 and when so moved projections 513 force member 510 toward member 509, clamping the bearing ring 506 therebetween and thus establishing driving connection between sheave 107 and shaft 108. Levers 512 are connected by links 515 to a movable collar 516 which carries pins 517 projecting therefrom.

Carried by the frame of the machine adjacent the panel slide is an operating lever which is secured to a horizontal shaft 521 having a laterally extending arm 522. A rod 523 is secured to the arm 522 and extends adjacent the lower portion of the frame to a point substantially under a clutch 500. A vertical clutch shifter shaft 524 is supported by the frame between upper and lower bearings and is connected by a crank arm 524' (Fig. 5) to connecting rod 523. At the upper portion of the shaft 524 is provided a slotted crank arm 525 best seen in Fig. 2. This arm is adapted to receive pins 517 in the slots thereof. It is therefore evident that motion of the lever 520 causes rotation of the slotted crank 525 and a corresponding engagement or disengagement of the clutch at will.

In Fig. 19 I have illustrated a panel with padding material applied thereto. The panel 400 which may be of any suitable shape, according to the use to which it is to be put, has areas of padding material 401, 402, 403, 404, 405, 406 and 407 applied thereto, leaving intermediate

spaces therebetween indicated at 408, 409, 410, 411, 412 and 413. It will also be noticed that around the periphery of the padding material are areas 415 to which no padding material is applied. As previously described, the panel board is coated with adhesive and when removed from the machine, the padding material in the accurately located areas referred to adheres thereto. By comparing Figs. 18 and 19, it will be seen that the knife edges 604 conform to the design which is to be imparted to the padding material. The panel portion as illustrated in Fig. 19 is ready for further processing which includes covering the same with upholstery material, forcing the upholstery material into the recesses 408 and 413 inclusive and securing the upholstery material therein to the panel board in some convenient manner, such for example as by an adhesive, by sewing, by vulcanization or other means.

Operation

The complete operation of my improved machine will now be described. Assuming that the parts are in the position shown in Fig. 1 and that the motor 105 is energized but that the clutch 500 is disconnected, the following are the procedural steps in the operation of the machine. A panel board is placed on the forward face of the panel slide 204, suitable fixtures being provided to accurately predetermine the position of the panel on the support. The lever 520 is now moved causing the clutch member 500 to be engaged and to impart rotation from the motor to shaft 108. The speed reducer 114 reduces the speed of rotation of the shaft 108 and rotates the gear 116 (see Fig. 2) at a predetermined relatively slow speed. Rotation of the gear 116 causes rotation of gear 117 meshed therewith and corresponding rotation of the toothed portion 120 and 120' of the member 119 (see Fig. 17) and a corresponding more rapid rotation of the annular members 122 and 122'. The lower portion 134' of annular member 122' will register with the driving slot 130' in the hub 121' and the driving key 129' will be spring pressed into locking engagement with the driving slot 130'. This will cause rotation of the driving member 127' shown beneath the gear 117 in Fig. 2. Driving member 127' will, as previously described, make one complete rotation and since this member is keyed to the shaft 110, shaft 110 will also make one complete rotation and stop.

Rotation of the shaft 110 through the crank 312 will cause links 304 to move first downwardly and then upwardly, the toggle arrangement provided by the links 303 and 304 permitting cutting roll assembly 300 to move in a vertical path over the face of the die member 600. The cutting roll assembly 300 will move downwardly a predetermined distance until the block 331 (see Fig. 4) engages the projection 333, at which time continued motion of the cutting roll assembly will cause movement of the chain 322 and corresponding motion of the shaft 335 driven by the one-way clutch assembly shown in detail in Fig. 7. Rotation of the shaft 335 causes corresponding rotation of the feed roll 320 and results in the downward feed of padding material over the face of the die 600, the lower edge of the padding material being always slightly above the cutting roll assembly.

When the cutting roll assembly reaches its lowermost position, finger 156, seen in Fig. 3, strikes valve lever 155, moving the same to low-

ermost position and connecting the interior of the die 600 to suction. Upward motion of the cutting roll follows and this upward motion is transmitted to chain 322, after a predetermined upward movement of the cutting roll, the motion of the chain 322 causing a corresponding reverse rotation of the sprocket 321 which, however, is ineffective to cause a corresponding reverse rotation of the shaft 335, due to the one-way clutch mechanism illustrated in Fig. 7. Upward motion of the cutting roll over the knife edges 604 of the die member 600, compresses the padding material against the knife edges and causes a severance of the padding material along all of the knife edges. The blocks of resilient material 605 are compressed as the cutting roll passes thereover, but as soon as the cutting roll has passed each block of resilient material, the block expands, forcing the cut padding material outwardly beyond the plane of the knife edges. Portions of the padding material which are not to be applied to the panel board as illustrated at 606 in Fig. 14, remain within the die between the knife edges. It should be recalled at this time that during this process the interior of the die is connected to suction so that the padding material even though expelled beyond the plane of the knife edges between blocks 605, will be retained against the faces of the blocks in substantially undistorted condition by suction.

When the cutting roll reaches its uppermost position, the crank 312 is moved substantially parallel to the slot 309 so that there is substantially no load on the parts. At this time the annular member 122' has rotated relative to the driving slot 130', such that a cam surface 133' forces the key 129' out of the driving slot. The driving member 127' thereupon comes to rest. At the same time the driving member 127 is connected to the driving slot 130 in the hub 121 by means of its spring pressed key and begins its single rotation. Rotation of this member is communicated to shaft 206 (see Fig. 2) by means of sprockets 207, 208 and chain 209. Rotation of the shaft 206 is transmitted to the crank 205 and by means of the link or connecting rod 204 this motion causes the panel slide 200 to move first toward and then away from the die 600. As previously described, means are provided for accurately adjusting the position of the slide relative to the die in its forwardmost position.

As the panel slide reaches its forwardmost position, trip 163 strikes the lever 164, releasing the valve lever 155, interrupting the communication between the die member and the vacuum supply. This releases the padding material, and such portions thereof as are projecting outwardly by resilient blocks 605 engage the surface of the panel board in exactly predetermined position and adhere thereto. The portions of the padding material which are not to be applied to the panel board remain within the confines of the die member between adjacent knife edges thereon. Upon return of the panel slide to its inoperative position, the roller 160 (seen in Fig. 3) strikes cam surface 159, thereby depressing operating arm 157 which in turn lifts valve arm 155 and connects the die member to a source of pressure. This pressure is effective to discharge the remaining portions of the padding material from the die, at which time the padding material falls into receptacle 350, from which it is withdrawn as by suction through a conduit 351 to a fabricating machine or waste receiver.

It may be stated at this time that the present

described mechanism is particularly adapted to be operated in combination with a fabricating machine which fabricates a continuous sheet of padding material and feeds the same forwardly over the conveyor 320 to the cutting mechanism. The unused portions of the padding material returned through the conduit 351 may then be refabricated, so that the whole comprises a closed system.

As the panel slide 200 reaches its inoperative or rearmost position, the cam surface 133 on the annular member 122 forces the driving pin out of engagement with the driving slot 130 and the panel support comes to rest.

By properly selecting the limits of the depressed portion 134 and properly selecting the number of teeth and gears 120, 122, 124 and 125, any desired cycle of operation may be obtained. For example, immediately upon the panel slide 200 coming to rest, the parts may be so related that the cutter roll starts its next cycle of operation. During this cycle of operation the completed panel may be removed from the panel slide and a second panel suitably coated with adhesive may be substituted therefor. If desired, a period of rest may be provided at this time during which neither panel slide nor the cutting roll are in motion. The selection of the relationship of parts as described will depend upon the desired safety factor, the time consumed by the operator in removing a finished panel slide and replacing the same, and the speed at which the mechanism is driven.

One of the primary advantages of the present machine resides in the fact that the padding material is exactly cut to a predetermined design and is applied directly to the panel board without being removed from the die member so that the padding material is applied to the panel board with a degree of precision which would be impossible, were manual means employed.

Aside from the great accuracy resulting from the use of the present machine, which substantially reduces the number of panels spoiled, the present machine substantially speeds up production. The machine is entirely automatic in operation and may be operated at a relatively high speed, care being taken only to provide a sufficient period for the operator to remove one finished panel from the panel support and to replace the same with a second panel.

The foregoing detailed description has been given for clearness of understanding only, and no unnecessary limitations should be understood therefrom, but the appended claims should be construed as broadly as permissible in view of the prior art.

What I claim as my invention is:

1. In the device described, a die, a cutter roll movable over said die, a sheet feeding means, and a plate support, driving means for actuating said sheet feeding means to feed sheet material over said die, driving means for moving said cutter roll over said die, and driving means for advancing said plate support toward said die, all of 65 said driving means being operated in sequentially timed relation.

2. In the device described, a knife edged die, a roll movable over said die, a panel support movable toward and away from said die, a driving part, means for continuously rotating said part, a first rotatable member having driving connection with said roll, a second rotatable member having driving connection with said panel support, means for connecting said part 75

and said first rotatable member for a predetermined rotation of said part to move said roll over said die, and for thereafter disconnecting the same, and other means for connecting said second rotatable means to said part for a successive rotation of the same to move said panel support toward and away from said die.

3. In the device described, a knife edged die, a roll movable over said die, a panel support movable toward and away from said die, a driving part, means for continuously rotating said part, a first rotatable member having driving connection with said roll, a second rotatable member having driving connection with said panel support, means for connecting said part and said first rotatable member for a predetermined rotation of said part to move said roll over said die, and for thereafter disconnecting the same, and other means for connecting said second rotatable means to said part for a successive rotation of the same, to move said panel support toward and away from said die said last recited means operative to cause successive rotation of said rotatable members and a successive interval of rest of said rotatable members.

4. In a device of the class described, a form-sustaining support comprising separate recessed parts for supporting separate pieces of sheet material, suction means for retaining certain pieces of said material within said support, means for elevating other pieces of said material at least partly out of said support, means for juxtaposing said support and an adhesive coated surface to apply said elevated pieces to said surface, and means effective subsequently to eject said remaining pieces from said support.

5. In a device of the character described, a cutting die, means for feeding a length of said material over said die, pneumatic means effective on said material, control means for said pneumatic means, means effective upon completion of the feeding operation to actuate said control means to apply suction to said material, compressing means for pressing said material against said die to cut said material into separate pieces, means for elevating some of said pieces at least partly out of said die, a panel support for supporting an adhesive coated panel, actuating means for moving said panel support toward said die to engage the adhesive coated surface of said panel against said elevated pieces, means operable in timed relation to movement of said support to operate said control means to interrupt the suction, thereby releasing said elevated pieces for adhesion to said panel, said actuating means adapted to move said support away from said die, and means operable after the initiation of said last mentioned motion for operating said control means to apply pressure to eject the balance of said cut material.

6. The method of applying padding material to a panel, comprising forcing said material into a plurality of recesses in a recessed, knife edged die, thereby cutting said material into separate pieces, retaining said material in some of said recesses and elevating material at least partly from other of said recesses, abutting an adhesive coated panel against said elevated material, removing said panel with said elevated material adhered thereto, and blowing said remaining material from said die.

7. A machine for cutting padding material into a desired pattern and for applying said cut padding material to a surface in said pattern comprising a die having elevated knife edges defin-

ing a plurality of separated areas, means for pressing sheet material against said knife edges to cut the same into pieces corresponding to said areas, means carried by said die for elevating the surface of some of said pieces above said knife edges, suction means for supporting said elevated pieces in elevated position, and means for thereafter juxtaposing said die and said surface for applying said elevated pieces to said surface.

8. A machine for cutting padding material into a desired pattern and for applying said cut padding material to a surface in said pattern comprising a die having elevated knife edges defining a plurality of separated areas, means for pressing sheet material against said die to cut the same into pieces corresponding to said areas, means carried by said die for elevating some of said pieces above said knife edges, said last means adapted to releasably support said elevated pieces in elevated position, means for thereafter juxtaposing said die and said surface for applying said elevated pieces to said surface, and means for releasing said elevated pieces from said die upon application to said surface.

9. A machine for cutting padding material into a desired pattern and for applying said cut padding material to a surface in said pattern comprising a die having elevated knife edges defining a plurality of separated areas, means for pressing sheet material against said die to cut the same into pieces corresponding to said areas, suction means retaining some of said pieces within said die, other means for elevating some of said pieces above said die, and means for thereafter juxtaposing said die and said surface for applying said elevated pieces to said surface.

10. A machine for cutting padding material into a desired pattern and for applying said cut padding material to a surface in said pattern comprising a die having elevated knife edges defining a plurality of separated areas, means for pressing sheet material against said die to cut the same, means retaining some of said cut pieces within said die, other means for elevating some of said pieces above said die and retaining the same against displacement from the said desired pattern in elevated position, and means for thereafter juxtaposing said die and said surface for applying said elevated pieces to said surface.

11. A machine for cutting padding material into a desired pattern and for applying said cut padding material to a surface in said pattern comprising a die having elevated knife edges defining a plurality of separated areas; means for pressing sheet material against said die to cut the same into pieces corresponding to said areas; said die including means for retaining some of said pieces within said die, and other means for elevating some of said pieces above said die and retaining the same in elevated position, drive means for juxtaposing said die and said surface to apply said elevated pieces to said surface, means effective thereupon to release said elevated pieces from said die, said drive means adapted to separate said die and said surface, and means effective thereafter for ejecting said remaining pieces.

12. In a device as described, a knife edge die adapted to cut a separated piece from sheet material, a block of resilient material within said die adapted to elevate said cut piece at least partly from said die, means comprising an air conduit opening on the exposed face of said

block and connecting to a source of suction for retaining said cut piece in elevated position on said block, and a carrier for a member having an adhesive coated surface movable toward said die to engage said surface with said elevated piece.

13. In a device of the class described a die having knife edges adapted to cut sheet material into a plurality of separate pieces; resilient means effective to elevate at least one piece above said knife edges; pneumatic means adapted to apply super-atmospheric, atmospheric, or sub-atmospheric pressure to all of said pieces of cut material to retain said elevated piece against said resilient means and to retain said non-elevated pieces in non-elevated position, to release all of said pieces, and to eject said non-elevated pieces respectively; a carrier for a member having an adhesive coated surface movable toward said die to engage said surface and said elevated piece, and movable away from said die; and control means for said pneumatic means to apply sub-atmospheric pressure to said pieces after cutting, to apply atmospheric pressure to said pieces when said surface engages said elevated piece to release said elevated piece for adherence to said surface, and to apply super-atmospheric pressure to eject the remaining pieces after said carrier moves away from said die.

14. A machine for cutting padding material into a desired pattern and for applying said cut padding material to a surface in said pattern comprising a die having partitions dividing an area into adjacent separate compartments adapted to receive material, means for elevating material in one of said compartments, pneumatic means operable on said material, means controlling said pneumatic means to apply suction, release suction and apply pressure to said material in succession, and means for moving an adhesive coated panel toward said die into contact with said elevated material while said pneumatic means applies suction, and for moving said panel away from said pattern after suction has been released, whereby said elevated material is adhesively applied in pattern form to said panel, and the remainder of said material is ejected from said die by the application of pressure.

15. A machine having a recessed, knife edge die, a relatively movable support for moving an adhesive coated panel toward and away from said die, a feeding support for sheet material adjacent one edge of said die, a roll normally adjacent said support, means for reciprocating said roll across said die away from and toward said feeding support in the order named, connections intermediate said roll and said feeding support to feed sheet material over said die as said roll moves away from said feeding support, and to interrupt the feed of said sheet material as said roll moves toward said support, and means for moving said support first toward and then away from said die.

16. A machine having a recessed, knife edge die, a relatively movable support for moving an adhesive coated panel toward and away from said die, a feeding support for sheet material adjacent one edge of said die, a roll normally adjacent said support, means for reciprocating said roll across said die first away from and then toward said feeding support, and adjustable connections intermediate said roll and said feeding support to feed a predetermined amount of sheet material over said die as said roll moves away from said support, and to interrupt the feed of

said sheet material as said roll moves toward said support, and means for moving said support first toward and then away from said die.

17. Means for cutting padding material from a sheet into a pattern and applying the cut padding material to a panel which comprises: a knife edge die structure having knife edges arranged in a desired pattern and adapted to cut said padding material into separate pieces, said die structure including pressure means for pressing sheet padding material against said knife edges to cut the same into separate pieces, said die structure including means effective upon actuation of said pressure means to cause some of said pieces to project in one direction beyond said die structure and to prevent other of said pieces from so projecting, a panel support adapted to position an adhesive coated panel in contact with said projecting pieces, and means for then separating said panel support and die structure.

18. Means for cutting padding material from a sheet into a pattern and applying the cut padding material to a panel which comprises: a knife edge die structure having knife edges arranged in a desired pattern and adapted to cut said padding material into separate pieces, said die structure including pressure means for pressing sheet padding material against said knife edges to cut the same into separate pieces, said die structure including means effective upon actuation of said pressure means to cause some of said pieces to project in one direction beyond said die structure and to prevent other of said pieces from so projecting, a panel support adapted to position an adhesive coated panel in contact with said projecting pieces, means for then separating said panel support and die structure, and means effective for discharging said other pieces from said die structure.

19. Means for cutting padding material from a sheet into a pattern and applying the cut padding material to a panel which comprises: a knife edge die structure having knife edges arranged in a desired pattern and adapted to cut said padding material into separate pieces, said die structure including pressure means for pressing sheet padding material against said knife edges to cut the same into separate pieces, said die structure including means effective on certain of said pieces to project said certain areas at least partly beyond said knife edges, and to retain said certain pieces in projected position, a panel support adapted to carry an adhesive coated panel, and means effective after projection of said certain pieces to first juxtapose said panel support and die structure to apply said projected pieces to said panel, and then to separate said panel support and die structure.

20. In a device of the class described, a die having upstanding knife edges defining a plurality of recesses, feeding means for locating sheet material over said knife edges, pressure means for forcing said sheet material against said knife edges so as to cut said sheet material into pieces and to press said cut pieces into said recesses, means cooperating with said die for moving some of said cut pieces outwardly of said die so that they project beyond the surface of the knife edges, suction means for preventing such outward movement of the other of said cut pieces, and means for advancing a panel into contact with said outwardly projecting pieces of sheet material.

21. A panel making machine comprising a frame, a flat recessed, knife-edged die carried by

said frame in substantially vertical relation, sheet feeding means carried by said die, means for intermittently actuating said sheet feeding means to feed a length of sheet material downwardly over said die, severing means movable against the knife edges of said die to cut said sheet material into separate parts and to force them into the recesses in said die, said die having means for moving some of said parts relatively outwardly of said die, and a panel carrier movable on said frame for advancing a panel carried thereby toward said die into contact with the outwardly moved parts of said sheet material.

22. In a device of the character described, a knife edge die adapted to cut a separated piece from sheet material, resilient means in said die beneath said piece adapted to elevate said cut piece at least partly from said die, means for retaining said cut piece in elevated position, and means for bringing an adhesive coated surface and said elevated cut piece of sheet material into engagement.

23. In a device of the character described, a knife edge die adapted to cut a separated piece from a sheet material, resilient means in said die beneath said piece adapted to elevate said cut piece at least partly from said die, suction means for retaining said cut area in elevated position against lateral displacement, means for bringing an adhesive coated surface into engagement with said elevated piece, and means effective thereafter for interrupting the suction to said suction means to release said piece for adherence to said adhesive coated surface.

24. A machine for cutting separate pieces of desired shape from sheet material and for applying said pieces in a desired design to the surface of a backing sheet which comprises: a flat, recessed, knife edge die, a roller movable across said die, feeding means for advancing said sheet material across said die, means for intermittently operating said roller, means for intermittently operating said feeding means in timed relation to operation of said roller, said die including means for holding certain of said pieces at least partly above the plane of the knife edges, a carrier for backing sheets movable toward and away from said die, means for intermittently operating said carrier in timed relation to operation of said feeding means and said roller operating means, and control means effective to cause operation of said feeding means and roller to advance sheet material over said die and to position said roller for a cutting traverse, to move said roller in a cutting traverse, and to advance said carrier toward said die to applying position and to move said carrier away from said die, in the order stated.

25. A machine for cutting separate pieces of desired shape from sheet material and for applying said pieces in a desired design to the surface of a backing sheet which comprises: a flat, recessed, knife edge die arranged substantially in a vertical plane, a roller movable across said die, feeding means for advancing said sheet material downwardly across said die, means for intermittently operating said feeding means, means for intermittently operating said roller in timed relation to operation of said feeding means, said die including means for moving certain of said pieces at least partly beyond the plane of said knife edges and for releasably supporting said pieces, a carrier for backing sheets movable toward and away from said die, means for intermittently operating said carrier in timed relation

to operation of said feeding means and said roller operating means, and control means effective to cause operation of said feeding means and roller to advance sheet material over said die, and to position said roller for a cutting traverse, to move said roller in a cutting traverse, and to advance said carrier toward said die to applying position and to move said carrier away from said die, in the order stated.

26. A machine of the class described comprising a die having knife edges defining separate recesses, sheet feeding means for feeding sheet material over said die, a roller movable over said die in cutting relation to the knife edges thereof, means in some of said recesses yieldable during the cutting operation to permit movement of cut pieces of said sheet material into said recesses during the cutting operation and effective thereafter to move said pieces at least partly beyond the plane of said knife edges, means effective thereafter for advancing a backing sheet into contact with said pieces, and means for thereafter ejecting the remainder of said sheet material from the other recesses of said die. 20

27. A machine of the class described comprising a die having knife edges defining separate recesses, sheet feeding means for feeding sheet material over said die, a roller movable over said die in cutting relation to the knife edges thereof, means in some of said recesses yieldable during the cutting operation to permit movement of cut pieces of said sheet material into said recesses during the cutting operation and effective thereafter to move said pieces at least partly beyond the plane of said knife edges, means for applying a holding force to said cut pieces to preserve their arrangement, means effective thereafter for advancing a backing sheet into contact with said pieces, means for thereupon releasing said holding force, and means for thereafter ejecting the remainder of said sheet material from the other recesses of said die. 30

28. In combination, a die, a carrier movable toward and away from said die, sheet feeding means adjacent one edge of said die, a cutting roll and carriage movable over said die toward and away from said feeding means, drive means for sequentially causing a reciprocation of said cutting roll carriage over said die first away from and then toward said sheet feeding means and then a reciprocation of said carrier first toward 40

and then away from said die, and means for operating said sheet feeding means during traverse of said cutting roll carriage away from said sheet feeding means.

5 29. In combination, a die, a carrier movable toward and away from said die, sheet feeding means adjacent one edge of said die, a cutting roll and carriage movable over said die toward and away from said feeding means, drive means for sequentially causing a reciprocation of said cutting roll carriage over said die first away from and then toward said sheet feeding means and then a reciprocation of said carrier first toward and then away from said die, and means for operating said sheet feeding means during traverse of said cutting roll carriage away from said sheet feeding means, said last recited means comprising means having a one-way mechanical driving connection with said cutting roll carriage. 15

30. A machine for cutting padding material into a desired pattern and for applying said cut padding material to a panel in said pattern comprising a knife edge, recessed die, a roll adapted to traverse said die, sheet feeding means adjacent said die, actuating means for causing said roll to traverse said die, means responsive to the traverse of said roll to feed sheet material over said die behind said roll, said actuating means being thereupon effective to cause said roll to re-traverse said die, cutting said sheet material against said die and forcing it into the recess, a panel support movable toward and away from said die and means for moving said panel support toward said die and away from said die during the interval between a cutting traverse of said roll and a succeeding traverse of said roll. 25

35 31. In combination, a die, a carrier movable toward and away from said die, sheet feeding means adjacent one edge of said die, a cutting roll and carriage movable over said die toward and away from said feeding means, drive means for sequentially causing a reciprocation of said cutting roll carriage over said die first away from and then toward said sheet feeding means and then a reciprocation of said carrier first toward and then away from said die, and means for operating said sheet feeding means intermittently between consecutive traverses of said cutting roll carriage toward said sheet feeding means. 45
